UNITED STATES PATENT OFFICE.

ABRAHAM POSNER, OF BROOKLYN, NEW YORK.

SHOE HEEL.

Application filed September 19, 1922. Serial No. 589,098.

To all whom it may concern:

Be it known that I, ABRAHAM POSNER, citizen of the United States, and resident of Brooklyn, in the county of Kings and 5 State of New York, have invented certain new and useful Improvements in Shoe Heels, of which the following is a specification.

This invention relates to improvements 10 in shoe heel structures and has as one of its objects to provide wear resisting devices anchored within the body of the heel and protruding through its outer lift in a manner to prevent inadvertent displacement of the lift in addition to the wearing qualities imparted.

Another purpose is in the production of a heel having means adapted to prevent a run-down condition, so objectionable from 20 the standpoint of appearance, economy and sanitation.

These and analogous aims are accomplished by the novel construction and arrangement of parts hereinafter described 25 and shown in the accompanying drawing, forming a material part of this disclosure, and in which:—

Figure 1 is a prospective view showing a shoe heel with the outer lift removed.

30 Figure 2 is a perspective view of a lug carrying lift plate used in the invention.

Figure 3 is a similar view of the outer heel lift used in connection.

Figure 4 is a side elevational view of a 35 conventional type of shoe, partially broken away at the heel to disclose the application of the device.

In the common type of shoe shown in the drawing, the numeral 10 designates the 40 sole extending from the toe at the front to the heel at the rear and carrying the vamp 11 and upper 12, an inner sole 13 being disposed in the usual manner.

A leather lift or plate 14 forms the first 45 element of the heel, a second lift 15 being superposed and both being firmly held by a curved row of slugs 16 having their inner ends 16' clinched below the inner sole and their outer ends arranged to project a substantially uniform distance as shown in 50 Figures 1 and 4.

A sheet metal plate 17 is shaped in profile to agree with the rear portion of the heel but of lesser area, the plate being provided with a series of perforations 18 adapted to pass freely over the extended

heads of the slugs 16, the plate being located and held thereby.

Fixed rigidly to the plate 17 are a plurality of metal lugs 19, three being shown 60 as preferable, the lugs being located at the extreme rear and on the side receiving the most wear.

An outer lift or plate 20, of leather, rubber or composition is formed with 65 openings 21, agreeing in shape, as oval rectangular or round, with the projecting lugs 19, the length of which is substantially equivalent to the thickness of the lift.

Lift 20 is applied to the heel in the condition indicated in Figure 1, the plate 17 being placed intermediate with the lugs 19 outward.

Upon the application of pressure the extending heads of the slugs 16 are forced 70 part way into the lift 20, as shown in Figure 4, and the process completed by inserting a marginal row of nails 22 securely affixing the heel lifts into a solid structure 75 in which the ends of the lugs 19 are level 80 with the outer surface of the lift 20 and due to their hardness prevent uneven wear at the points of hardest contact of the heel and surface trodden upon.

As changes of construction could be made 85 within the scope of the invention, it is expected that the foregoing description and showing be regarded as illustrative rather than limitative as will be understood.

I claim:—

1. A shoe heel comprising two or more lifts, an arcuate row of slugs passing through said lifts into the shoe sole, the heads of said slugs extending outwardly, a metal plate having perforations registering with certain of said slugs, an outer lift in which the heads of said slugs are imbedded, said outer lift having openings near its rear and side edges, metal lugs fixed with said plate extending through the 95 mentioned openings in said outer lift, and a marginal row of nails passing through all of said lifts exteriorly of the edge of said plate.

2. A shoe heel comprising two or more 105 fixed lifts, slugs driven through said lifts into the shoe sole and clinched on the opposite side thereof, the heads of said slugs extending outward beyond the surface of the outermost of said fixed lifts, 110 an outer lift containing apertures, said outer lift being pressed forcibly to receive the

extending heads of said slugs, a relatively exposed surface, and a marginal row of thin metallic plate interposed between said outer lift and the outermost of said fixed lifts, said plate being perforated to pass over said slugs, a plurality of lugs extending outwardly from said plate into the apertures of said outer lift level with its

10 exposed surface, and a marginal row of nails passing through said outer lift into the heel structure.

Signed at New York, in the county of New York and State of New York, this 15th day of September, A. D. 1922.

ABRAHAM POSNER.
